ADHESIVE APPLYING MECHANISM

Edwin G. Staude, Minneapolis, Minn.

Application June 25, 1932. Serial No. 619,291

16 Claims. (Cl. 91—50)

This invention relates to improvements in adhesive applying mechanism and is particularly applicable to the type of machine shown in my application Serial Number 492,441, filed October 5, 1930. The mechanism may be used generally, and also for applying adhesive to boxboard blanks handled on ordinary paper box machines.

The primary object of the invention is to provide an adhesive-applying mechanism which will 10 successfully handle an adhesive which is very "stringy", or "tacky", adhesive of such character being necessary to attach moisture-proof cellulosic material to box blanks or the like.

The invention consists primarily in the provision of a roll or other moving member, which is moved in synchronism with the adhesive delivery roll in a manner to return any surplus adhesive to the receptacle.

The invention is particularly valuable for preventing leaks. Ordinarily leaking glue smears the carrying belts, and the work. The least blemish on the work renders it unfit for commercial use. In the case of cartons for various commodities, it is required that they be absolutely clean. 25 This requirement for cleanliness is so strict that those who examine the work use magnifying glasses to detect the blemishes, and any box which has the least smear or blemish is discarded. Great losses are, therefore, occasioned as a result of 30 the escaping surplus adhesive. Moreover, there is about a ten per cent loss of adhesive when the ordinary delivery mechanisms are operating. By the use of the present invention, there is no loss of adhesive, and no smearing whatever.

35 Features of the invention include: the provision of a moving member which forms a part of the wall of the adhesive receptacle; the location of the member so as to catch or pick up all surplus adhesive; the operation of this member to move 40 in a manner to return any surplus adhesive to the receptacle; the use of a revolving member, arranged below the adhesive supply or delivery roll and the roll to which adhesive is delivered, so that any surplus adhesive may fall by gravity 45 onto it; to so space the roll relative to the other rolls that capillary and surface tension actions are taken advantage of to positively prevent dripping; to give the member a predetermined directional rotation relative to the adhesive supply or 50 delivery roll; to give this member a predetermined direction of rotation in relation to the adhesive supply roll and to the roll to which adhesive is delivered; to provide an adjustable scraper member which engages and cooperates with the pick-up member to form the forward wall of the ad-

hesive receptacle; to have the pick-up or adhesive catch member in constant contact with the adhesive of the receptacle; and generally to provide a mechanism which is useful for any purpose inherent in the disclosure.

55 Features of the invention also include, along with the broader ideas of means, all details of construction shown in the drawings, or mentioned in the description, or claimed.

60 Objects, features and advantages of the invention will be set forth in the description of the drawings forming a part of this application, and in said drawings

65 Figure 1 is a top plan of my improved adhesive applying mechanism;

70 Figure 2 is an end view of Figure 1;

75 Figure 3 is a vertical section on line 3—3 of Figure 1, including part of a blank-feeding mechanism with which the present adhesive applying device is now used;

80 Figure 4 is an end elevation with the bearings for the movable surplus-intercepting-and-returning means in section; and

85 Figure 5 is an enlarged detail section illustrating the manner in which the drippings or stringing adhesive is wiped against the moving surface, and is returned to the reservoir.

90 The entire adhesive mechanism is herein disposed above the line of feed of the work so as not to interfere with the movement of the material to which the adhesive is to be applied. The work, therefore, passes beneath the gluing mechanism. For this reason, the space is necessarily limited, since the diameters of the plate cylinders are determined by the range of the machine.

95 In the drawings, 2 represents a mechanism for carrying the article to which the adhesive is to be applied through the machine. Numeral 3 indicates a drum to which the adhesive is delivered, and the drum has a plate 4 for receiving the adhesive. The drum 3 is mounted on a shaft 5. The article to which the adhesive is to be applied is held against the plate 4 by the rolls 6—6.

100 Numeral 7 indicates a cross member or spreader to which the device is attached. This embodiment includes a frame 8, attached to the spreader by cap screws 9, fitting in slots 10, and tapped into beveled nuts 11, see Figures 2 and 3. The frame can thus be adjusted in direction of feed. 105 This frame 8 carries a reservoir 12 for adhesive 13.

110 Mounted within the reservoir 12 is a drum 14 immersed in the adhesive 13. This drum constitutes an adhesive supply or delivery means. A

scraper device 15 regulates the flow of adhesive on the drum 14. By means of a lever 16 and thumb screw arrangement 17, the scraper is adjusted. A spring 18 holds the scraper 15 normally in the "out" or "off" position. By manipulating the thumb screw 17, the scraper 15 is caused to assume the proper operative relation with the surface of the drum 14.

Ahead of the drum 14, in direction of feed, 10 there is mounted a roller 19, in this embodiment adapted to rotate in clockwise direction, or in a direction opposite that of the drum 14. The movable means 14 may take other forms, to perform its function of intercepting, and returning 15 surplus adhesive to the reservoir. The location of the roller 19 is such that it retains the adhesive 13 within the reservoir 12, and, therefore, forms a part of the wall of the reservoir. An adjustable member 20, held in position by cap screws 20 21, cooperates with roll 19 to prevent leakage of adhesive by acting as a scraper. Referring to Figure 3, the roller 19 is positioned directly below the apex formed by the drum 14, and the adhesive-transferring plate 4 of drum 3.

25 In practice, I find that where the adhesive is very heavy, a stringing action takes place as the plate 4 leaves the surface of the drum 14, and when the member 19 is stationary, this results in draining off and soon outside dripping occurs 30 to be deposited upon the work. It is, therefore, impracticable to run adhesive that is very thick because it requires too frequent "wiping up".

By revolving the roller 19 in a predetermined direction, any drippings will immediately be carried into the reservoir 12, and by use of the 35 scraper 20, a clean surface member 19 is constantly opposed to the plate 4.

It is to be noted that the rotative wall-forming element of the glue reservoir is located in 40 position to the meeting or transfer points of the rolls 3 and 14, so that it acts as a moving shield to intercept and return the surplus adhesive to the reservoir. The roll 19 is operated at a speed greater than the speed of motion of the glue, 45 due to action of gravity, and is varied conformably to the degree of viscosity of the adhesive. In this instance, the variation may be accomplished by changing the gear ratios.

In order to drive the movable means 19, there 50 is provided a gear 22, see Figures 1 and 4, meshing with a gear 23, mounted on a shaft 24, which same shaft drives the drum 14. On the outside of the gear 23 is mounted a gear 25 which meshes with a gear 26 mounted on the shaft 5 of the 55 feeding machine.

In order to adjust the drum 14 relative to plate 4, there is provided a set screw arrangement 27, see Figure 2.

Since the distance between the side walls of 60 the adhesive reservoir and the length of roller 19 must be the same to maintain an adhesive-tight joint, and since adjustment is necessary to maintain such a condition, there is provided, see Figure 4, a threaded bushing 28 having a jam nut 65 29, to take up any lateral slack. Since the scraper member 20, see Figure 3, is of exactly the same length as the distance between the reservoir side walls and also the same length as the roll 19, one can, with this adjustment of the threaded bushing 28, provide a very inexpensive and practical adjustment.

In order to reduce evaporation of the adhesive 13, there is provided a cover 30 which is hinged 75 at 31.

I claim as my invention:

1. A device of the class described having a receptacle for adhesive, an adhesive supply roll operatively associated with the receptacle, movable means forming a part of the wall of the receptacle and in contact with the adhesive, and disposed to intercept surplus adhesive of the supply roll and return it to the receptacle, and means for moving said intercepting and returning means in a manner to return surplus adhesive to the receptacle. 80

2. A device of the class described having a receptacle for adhesive, an adhesive supply roll operatively associated with the receptacle, and a pick-up roll forming a part of the wall of the receptacle and in contact with the adhesive, and disposed to intercept surplus adhesive of the supply roll and return it to the receptacle, and means operating the pick-up roll to return the surplus to the receptacle. 85

3. A device of the class described having a receptacle for adhesive, an adhesive supply roll operatively associated with the receptacle, a roll to which the adhesive is delivered, and an adhesive pick-up roll forming a part of the wall of the receptacle and in contact with the adhesive, and disposed to intercept surplus adhesive of the supply roll and return it to the receptacle, and means for synchronizing motion of the rolls and directionally moving them in a manner to return 100 surplus adhesive to the receptacle. 105

4. A device of the class described having a receptacle for adhesive, an adhesive supply roll operatively associated with the receptacle, a roll to which the adhesive is delivered, and an adhesive pick-up roll forming a part of the wall of the receptacle and in contact with the adhesive, a scraper member engaging the pick-up roll and cooperating therewith to complete the wall and to prevent delivery of adhesive by the roll to a 110 point outside the receptacle, and means operating the rolls in a manner to return surplus adhesive to the receptacle. 115

5. A device of the class described having a receptacle for adhesive, an adhesive supply roll operatively associated with the receptacle, and an adhesive pick-up roll adjacent the supply roll and forming a part of the wall of the receptacle and in contact with the adhesive, and means operating the rolls to cause the surfaces of the supply and pick-up rolls to move in the same direction and toward the receptacle at that point at which their surfaces are nearest together. 120 125

6. A device of the class described having a receptacle for adhesive, an adhesive supply and delivery roll operatively associated with the receptacle, a roll to which the adhesive is delivered, and an adhesive pick-up roll forming a part of the wall of the receptacle and in contact with the adhesive, a scraper member engaging the pick-up roll and cooperating therewith to complete the wall and to prevent delivery of adhesive by the roll to a point outside the receptacle, said roll being disposed to catch surplus adhesive dropped by gravity from the other rolls and to carry it into 130 the receptacle, and means operating the rolls in a manner to return surplus adhesive to the receptacle, the supply and pick-up rolls being moved in the same direction and toward the receptacle at that point at which their surfaces are nearest 135 together, and said rolls being closely spaced, and the pick-up roll being placed below the point of nearest approach of the supply roll and the roll to which the adhesive is delivered. 140

7. A device of the class described having a re- 150

ceptacle for adhesive, an adhesive supply roll operatively associated with the receptacle, a roll to which the adhesive is delivered, an adhesive pick-up roll forming a part of the wall of the receptacle and in contact with the adhesive, and having a portion opposed to said roll to which the adhesive is delivered, and a scraper member engaging the pick-up roll to prevent delivery of adhesive by the roll to a point outside the receptacle, and to maintain a clean condition of the roll in that portion which is opposed to the roll to which the adhesive is delivered.

8. A device of the class described having a receptacle for adhesive, an adhesive supply roll operatively associated with the receptacle, a roll to which the adhesive is delivered, an adhesive pick-up roll in contact with the adhesive, and arranged below said rolls and close to both, but nearer the supply roll, means for operating the rolls to cause the surfaces of the supply and pick-up rolls to move in the same direction and toward the receptacle at that point at which their surfaces are nearest one another, and means for preventing delivery of adhesive to that portion of the pick-up roll which is opposed to that roll to which the adhesive is delivered.

9. A device of the class described having a receptacle for adhesive, an adhesive supply roll operatively associated with the receptacle, a roll to which the adhesive is delivered, an adhesive pick-up roll forming a part of the wall of the receptacle and in contact with the adhesive and a scraper member engaging the pick-up roll and cooperating therewith to prevent delivery of adhesive by the roll to a point outside the receptacle, and to maintain a clean condition of the roll in that portion which is opposed to the roll to which the adhesive is delivered, the surface of said pick-up roll being near to both of the other rolls, but nearer to the supply roll.

10. A device of the class described having a receptacle for adhesive, an adhesive supply roll operatively associated with the receptacle, a roll to which the adhesive is delivered, an adhesive pick-up roll in contact with the adhesive, the surfaces of said rolls being near one another, but the surface of the pick-up roll being nearest the surface of the supply roll, and means operating the rolls to cause the surfaces of the supply and pick-up rolls to move in the same direction toward the receptacle at that point at which their surfaces are nearest one another, and to cause the surfaces of the pick-up roll and the remaining roll to move in opposite directions at that point at which their surfaces are nearest one another.

11. A device of the class described having a receptacle for adhesive, an adhesive supply roll operatively associated with the receptacle, a roll to which the adhesive is delivered, an adhesive pick-up roll in contact with the adhesive in the receptacle, and close to the other rolls, and means

operating the rolls to cause the surfaces of the supply and pick-up rolls to move in the same direction in that region at which their surfaces are nearest, and to cause the surface of the pick-up and the remaining roll to move in opposite directions at that point at which their surfaces are nearest one another.

12. A device of the class described having a receptacle for adhesive, an adhesive supply roll operatively associated with the receptacle, a roll to which the adhesive is delivered, an adhesive pick-up roll forming a wall of the receptacle and in contact with the adhesive, and close to the other rolls, and means for operating the rolls to cause the surface of the supply and pick-up rolls to move in the same direction in that region at which their surfaces are nearest to one another, and to cause the surface of the pick-up roll and the remaining roll to move in opposite directions in that region at which their surfaces are nearest.

13. A device for handling tacky, stringy adhesive used in attaching moisture-proof cellulosic material to box blanks, comprising a receptacle containing a supply of adhesive, first and second rolls both in contact with the supply of adhesive, a third roll adjacent said rolls and to which the first roll delivers adhesive, and means for operating the rolls to cause the approximate surfaces of the first and second rolls to move toward the glue supply.

14. A device for handling tacky, stringy adhesive used in attaching moisture-proof cellulosic material to box blanks, comprising a receptacle for adhesive, first and second rolls forming one side of the glue receptacle and both in contact with the supply of adhesive, a third roll adjacent said rolls and to which the first roll delivers adhesive, and means for operating the rolls to cause the approximate surfaces of the first and second to move towards the glue supply.

15. A device for handling tacky, stringy adhesive used in attaching moisture-proof cellulosic material to box blanks comprising a receptacle for adhesive, first and second rolls forming one side of the glue receptacle and both in contact with the supply of adhesive, a third roll to which the first roll delivers adhesive and having its periphery adjacent the second roll, with the delivery point above the second roll, and means for operating the rolls to cause the approximate surfaces of the first and third rolls to move downwardly and the approximate surfaces of the first and second to move towards the glue supply.

16. A device of the class described comprising a receptacle containing a supply of adhesive, first and second rolls both in contact with the supply of adhesive, a third roll adjacent the rolls and to which the first roll delivers adhesive, the second roll moving downwardly at the point of contact with the third roll, and moving toward the second roll and downwardly toward the receptacle.

EDWIN G. STAUDE.
